UNITED STATES PATENT OFFICE.

MORRIS SHEINMAN, OF NEW YORK, N. Y.

LOCK.

1,413,137.

Specification of Letters Patent. Patented Apr. 18, 1922.

Application filed May 16, 1921. Serial No. 469,753.

To all whom it may concern:

Be it known that I, MORRIS SHEINMAN, a resident of New York city, Bronx County, State of New York, and a citizen of the 5 United States of America, have invented certain new and useful Improvements in Locks, of which the following is a specification.

This invention relates to improvements in 10 locks, more particularly door locks, one of the objects of my invention being to provide a lock that is proof against a jimmy or instrument to force the lock-members apart in order that the bolt will clear the keeper 15 whereby the door can be opened. A further object of the invention is to provide, in combination with a jimmy-proof lock, an alarm mechanism arranged to cooperate with the lock to give notice that an attempt 20 is being made upon a door to force the lock. A further object of the invention is to provide a spring lock, the bolt of which can be rendered dead after it has been locked, that is to say, locked against movement excepting 25 by the use of a proper key or knob. The above are merely outlines of my invention, a more detailed description of which will hereinafter appear.

In the accompanying drawings, which illustrate an embodiment of my invention:—

Fig. 1 is a face view of my improved lock (the cover being removed) and the cooperating keeper, which is shown in section;

Fig. 2 is an enlarged sectional view, the section being taken on a line 2—2 in Fig. 1;

Fig. 3 is an enlarged sectional view of the keeper, the section being taken on a line 3—3 in Fig. 1;

Fig. 4 is a face view of a portion of the 40 lock, illustrating the releasing of the latch thereof;

Fig. 5 is a similar view of the lock and keeper which is illustrated in section, illustrating the position of the parts when the 45 mechanism is locked and rendered dead;

Fig. 6 is an enlarged sectional detail view, illustrating one of the contacts included in the alarm circuit;

Fig. 7 is an enlarged fragmentary sectional view, illustrating the connection between the lock mechanism and a cylinder lock;

Fig. 8 is a cross sectional view, the section being taken in line 8—8 in Fig. 1; and

Fig. 9 is a fragmentary cross sectional

view, the section being taken on a line 9—9 in Fig. 1.

My improved lock consists of a casing member 10 within which is mounted a slideable expandable bolt 11, said bolt passing through the wall 12 of the casing to engage a keeper 13 which will be mounted, as usual, upon the frame member 14 of a door (see Fig. 2), which is not shown. The casing 10 will of course be secured to a door, a portion of which is indicated by 15. The casing 10 will be mounted upon the inside face of the door, and the keeper on the face of the door-frame adjacent the casing 10. The lock for operating the bolt may be of any well known type, preferably of the pin cylinder type operated with a paracentric key and will be a sunken lock, that is to say, mounted within the door, as indicated by dotted lines 17 in Fig. 2, and by full lines in Fig. 7. The pin cylinder 17 will operate a cam or roll-back 19 within the casing 10 by the usual spindle connection or plate 20 which operates a hollow cylinder 21. The cylinder 21 carries a tongue 22 which rests within a jaw 23 in the cam 19. The cam 19 will, of course, be rotatably mounted and also movable longitudinally of its axis in order that tongue 22 can be withdrawn from the jaw 23 for a purpose to be described. In this instance, cam 19 is mounted within a socket 24 in casing 10 and is backed by a compressible spring 25 which surrounds a spindle 26 which at its outer end has secured thereto a knob 27 by which means the cam can be moved, longitudinally of its axis, against the tension of spring 25, to cause the tongue 22 to clear the jaw 23. When cam 19 is moved, as above described, it can be rotated to operate bolt 11 independently of cylinder 17. The knob 27 will be located on the inside of the door; hence, bolt 11 can be operated from within a room even though the door has been locked from the outside. To operate the bolt, the cam 19 will include a finger 28, in the form of a hook, in this instance, to contact with a lug or projection 29 carried by the plate portion 30 of the bolt 11. The plate 30 will be bifurcated and provided with guide members 31 and 32 which straddle the cam 19, the guide 31 bearing against a post 33 and the guide 32 against a post 34 carrying a lip 35 to be engaged by a latch or tumbler 36 carried by a plate 37 positioned over the plate 30 of bolt 11, but not secured thereto.

- The plate 37 is arranged for movement transversely of the direction of movement of bolt 11 to operate anti-jimmy hooks 38, 38^a carried by the bolt 11, said hooks being pivotally connected to said bolt at 39. The inner ends 40 of the hooks project into casing 10 in order that they can be actuated by the transversely movable plate 37, the outer end of each hook 38, 38^a, being arranged, when 5 10 15 20 25 30 35 40 45 50 55 60 65 70 75 80 85 90 95 100 105 110 115 120 125 130 said hooks are moved upon their pivots, to project beyond the sides of the bolt 11, as indicated in Fig. 5. The hooks 38, 38^a will, when the door is unlocked, be positioned within the bolt 11, as indicated in Fig. 1, being held in such position by a spring 41. The bolt 11 will normally project beyond the casing 10, being held in such position by a spring 42 which is anchored, intermediate its ends, to a post 43 carried by the transversely movable plate 37. The post 43 also pivotally supports the latch 36. The leg 45 of spring 42 bears against a post 46 carried by plate 30, while the leg 47 of said spring bears against latch 36. The spring 42 will force bolt 11 outwardly and latch 36 toward the lip 35 on post 34. The function of latch 36 is to prevent movement of plate 37 transversely of the casing 11 in order that said plate can be locked, and operable only by the cam 19. The latch 36 will be provided with a nose piece 48 to engage lip 35 to lock plate 37 against movement. In Fig. 1, plate 37, is illustrated as locked against movement to prevent actuation of the hooks 38, 38^a. To prevent movement of plate 37, longitudinally of the casing, when acted upon by the cam 19, I provide said plate with depending flanges 49 and 50 (see Fig. 8), having slots to engage guides 51 and 52 carried by the casing 10 (see also Fig. 2). The plate 37 will slide upon the guides 51 and 52 when acted upon by the cam 19 which carries a finger 53 to actuate said plate 37 and also latch 36. To enable finger 53 to actuate the latch 36, I provide same with a nose piece 54 which projects outwardly and is located between lugs 55 and 56 carried by the transversely movable slide 37. The nose-piece 54 projects slightly beyond the face of lug 55 and lug 56; hence, the latch 36 is the first to be operated when cam 19 is actuated. To operate the hooks 38, 38^a, plate 37 is provided at one end with an arm 57 to actuate hook 38 and at the other end with a jaw 59 to actuate a lever 60 which in turn operates hook 38^a, the lever 60 being pivotally supported by a pin 61 carried by the casing 10.
- In combination with the lock mechanism, 60 I employ an alarm device, in this instance a bell 62, operated from a source of electrical supply 63, said bell and source of supply being in circuit with (in this instance) two contacts 64 and 65 carried by the keeper 13 but insulated therefrom, as can be seen in Fig. 6, a detailed description of the manner of insulating the contacts being omitted, as it may be accomplished in any desirable manner. The circuit for the bell 62 will be closed by the hooks 38, 38^a, when said hooks are in locking position should the door be forced sufficiently to cause said hooks to touch said contacts. Under normal conditions the hooks will be out of contact with the contacts 64 and 65, as can be seen in Fig. 75 5. The keeper 13 will be provided with a striker 66 to force the bolt inwardly against the tension of spring 42 when the door is being shut, as said bolt will normally project beyond the adjacent edge of the door, being yieldably held in such position by said spring 42.
- The device operates as follows:
- To lock the door, after it has been closed, a paracentric key will be inserted into pin 85 cylinder 17 and turned, which operation will turn cam 19. To lock the door the cam will be turned as per the arrow 67, Fig. 1. The first element to be moved will be the latch 36 which will be moved away from lip 35 (see Fig. 4); the releasing of the latch 36 will free plate 37. A continued movement of the cam will cause finger 53 to contact with lug 55 and force plate 37 transversely of the casing (see Fig. 5), which movement will cause arm 57 to move hook 38 upon its pivot and lever 60 to move hook 38^a upon its pivot. The movement of hooks 38, 38^a will cause the outer ends to move outwardly beyond the sides of the bolt 11. After plate 27 has been moved to its full extent and finger 53 moved away therefrom, spring arm 47 will force the nose-piece 68 on latch 36 under lip 35, as will be evident from an inspection of Fig. 5. The plate 37 will now be locked against a return movement; hence, hooks 38, 38^a will be latched in locking position. The plate 37 can, however, be returned to normal position by turning the cam 19 in opposite direction by turning the pin cylinder 17 by means of 90 95 100 105 110 115 120 125 130 the key. The pin cylinder as has been stated, will be located on the outside of the door and the knob 27 on the inside.
- Should it be necessary to unlock the door, from the inside, even though it be locked from the outside, the knob 27 can be pulled in the direction of the arrow 69, Fig. 7, which will cause the jaw 23 to clear the cylinder 21, after which the cam can be rotated to cause finger 53 to operate the latch 36 and plate 37. When the door is not locked, hooks 38, 38^a will be positioned to permit actuation of the bolt 11 by the movement of the cam 19 in the direction of the arrow 70, Fig. 1, in which instance finger 28 will contact with projection 27 on plate 30 of bolt 11, and force the bolt to the left in Fig. 1, against the tension of the spring 42. The hooks 38, 38^a are provided for the purpose of preventing the withdrawal of the

bolt 11 from the outside of the door excepting by means of a proper key and also to prevent the forcing of the door away from the door frame. Should an attempt be made 5 to force the door away from the frame, by the insertion of an instrument in the space 71, the hooks 38, 38^a would contact with the wall 72 of the keeper 38 and prevent further movement, or rather with the contacts 64 10 and 65, which would close the circuit for the bell 62; hence, said bell will ring and indicate that the door is being forced. It will be evident that the hooks 38, 38^a not only act to prevent the forcing of the door, 15 but also act as a switch to close the circuit for the alarm, no other switches being necessary. The cylinder 17 is, in this instance, mounted upon the cover plate 73 for the casing 10 which is secured to the casing 10 20 by screws 74 which engage the posts 33 and 34. The casing and its plate will be secured to the door by screws 75 which pass through the casing and its cover plate 73.

Under normal conditions, that is to say, 25 when hooks 38 and 38^a are not locked against movement, or rendered dead, the lock will act as an ordinary spring latch, the bolt 11 being free to be moved inwardly by a key or knob 27. My improved lock has four 30 distinctive points, namely, it is an alarm lock; it can be made a dead lock; it will act as a spring latch, and is also a jimmy proof lock.

What I claim and desire to secure by Letters Patent is:—

1. In a lock mechanism, a casing, a bolt movable longitudinally thereof, a plate movable transversely of the casing, a latch carried by the plate to lock same against movement, means carried by the casing to engage the latch, supplemental locking means carried by the bolt, arranged for operation by said transversely movable plate, and a key or knob operated mechanism arranged to 45 firstly operate the latch to release said plate, and thereafter to operate the plate to actuate the supplemental locking means.

2. In a lock mechanism, a casing, a bolt movable longitudinally thereof, a plate movable transversely of the casing, a latch carried by the plate to lock same against movement, means carried by the casing to engage the latch, supplemental locking means carried by the bolt arranged for operation by 55 said transversely movable plate, a cam carried by the casing to actuate said plate and latch carried thereby, a key or knob operated mechanism, releasably connected to the cam, to operate the cam, and means to disengage the cam from the key operated mechanism whereby said latch and plate can be operated independently of the key or knob operated mechanism.

3. In a lock, a bolt, an anti-jimmy device 60 carried by said bolt, means for moving the

anti-jimmy device into operative position and a detent for normally holding the anti-jimmy device in in-operative position.

4. In a lock, a bolt, an anti-jimmy device carried by the bolt, and a detent adapted to 70 lock the anti-jimmy device in both an operative and in-operative position.

5. In a lock, a bolt, an anti-jimmy hook and a revoluble cam and a member for operatively engaging the anti-jimmy hook, the 75 cam adapted to engage the member and move it transversely of the bolt.

6. In a lock, a bolt, an anti-jimmy device carried by the bolt and means for operating the same and a swinging tumbler for locking 80 the anti-jimmy device.

7. In a lock, a bolt, an anti-jimmy device carried by the bolt and means for operating the same and a locking tumbler carried by the operating means.

8. In a lock, a strap bolt bent in U-form and an anti-jimmy device carried within the U.

9. In a lock, a bolt, an anti-jimmy hook, a revoluble cam for the bolt and a member 90 adapted to engage the hook and to be engaged by said cam and to be moved by said cam transversely of said bolt.

10. In a lock, a bolt, a pair of pivoted anti-jimmy hooks carried one upon each 95 side of said bolt, a member movable transversely of said bolt and adapted to engage one of said hooks, a lever, the lever adapted to be moved by said transversely moving member and to engage the other of said 100 hooks to move the same.

11. In a lock, a bolt, a pair of anti-jimmy hooks, a rotating cam for the bolt, a member straddling the bolt between the cam and hooks and movable transversely of the bolt 105 by the cam and adapted to move one of the hooks in one direction and another of the hooks in another direction.

12. In a lock, a bolt, a roll back for the bolt an anti-jimmy device, a slide movable 110 by the roll back for operating the anti-jimmy device, and a swinging locking tumbler carried by said slide.

13. In a lock, a strap bolt, the nose of which is bent in U-form, a pair of anti-jimmy hooks one upon each side of the bolt, triple pins joining the sides of the U, one of the pins mounting one of the hooks, another of the pins mounting another of the hooks and a spring carried by the third 120 pin and engaging both of the hooks.

14. In a lock, a bolt, an anti-jimmy device, a member for operating the anti-jimmy device, a swinging locking tumbler carried by the member, a pivot pin for the swinging tumbler, and a spring carried by the pivot pin adapted to urge the bolt in one direction and the tumbler in an opposite direction.

15. In a lock, a spring-urged automati- 130

cally retracted bolt, a roll-back and means carried by the bolt for engagement by the roll-back, an anti-jimmy device carried by the bolt and a clearance between the roll-back and bolt, whereby, when the roll-back is locked, the bolt may move from operative to in-operative position.

16. In a lock, a spring-urged bolt, an anti-jimmy device and a roll-back adapted 10 to retract the bolt and to operate the anti-jimmy device.

17. In a lock, a bolt, an anti-jimmy device carried by the bolt, a roll-back adapted to retract the bolt and to move said anti-jimmy device into an operative position by 15 a movement in a reverse direction and spring means for projecting the bolt and retracting the anti-jimmy device.

18. In a lock, a sliding bolt, an anti-jimmy device, a casing, a member slidable upon 20 the casing transversely of the bolt and a roll-back adapted to engage the slidable member to slide the same, the slidable member adapted to move the anti-jimmy device.

25 19. In a lock, a bolt, a pair of anti-jimmy hooks, a casing, a lever pivoted to the casing, a member slidable transversely of the casing and adapted to move one of the hooks and also to move the lever.

30 20. In a lock, an expansible bolt, a roll-back, a member movable transversely to the bolt to expand the bolt, a tumbler pivoted upon and carried by said member, the tumbler extending entirely across the bolt, a lug 35 projecting from the side of the bolt opposite the pivot of the tumbler and adapted to engage the tumbler to hold the sliding member locked against movement.

21. In a lock, a roll-back, an anti-jimmy 40 device, a carriage inter-connecting the roll-back and anti-jimmy device and provided with a face adapted to engage the roll back and a tumbler mounted upon the carriage and also provided with a face adapted to 45 engage the roll-back.

22. In a lock, a sliding bolt, a pair of anti-jimmy hooks, a keeper, the hooks re-

moved from and spaced in relation to the wall of the keeper when in projected position.

50 23. In a lock, a roll-back, knob and key mechanism for operating said roll back, a spring-urged expansible bolt, the roll-back adapted to expand and retract the bolt and means inter-connecting the knob and key mechanism adapted to be dis-connected by a pre-determined movement of the knob.

24. In a lock, a roll-back, knob and key mechanism for operating said roll back, a spring-urged expansible bolt, the roll-back 60 adapted to expand and retract the bolt and means inter-connecting the knob and key mechanism adapted to be disconnected by a pre-determined movement of the knob, the disconnecting means including a rabbet and 65 tongue.

25. In a lock, a spring-urged expansible bolt normally yieldingly held unexpanded.

70 26. In a lock, a spring-urged expansible bolt normally yieldingly held unexpanded, and a common member for retracting and expanding the bolt.

27. In a lock, a spring-urged expansible bolt yieldingly held unexpanded, and means for locking the bolt in both expanded and 75 unexpanded position.

28. In a lock, a roll-back, an anti-jimmy device, a bolt, a carriage inter-connecting the roll-back and anti-jimmy device and provided with a face adapted to engage the 80 roll-back and a tumbler mounted upon the carriage and also provided with a face adapted to engage the roll-back, the carriage provided with a guide for the tumbler in juxtaposition to said faces.

85 29. In a lock mechanism, a movable bolt, a movable cam to operate the bolt, a key operated device releasably connected to said cam arranged to actuate the cam to operate said bolt, and means to disengage the cam and lock mechanism whereby said cam can be moved to actuate independently of the lock mechanism.

MORRIS SHEINMAN.
